EUSTIS P. MORGAN, OF SACO, AND JAMES H. McMULLAN, OF BIDDEFORD, MAINE.

Letters Patent No. 90,378, dated May 25, 1869.

IMPROVEMENT IN ROVING-FRAME.

The Schedule referred to in these Letters Patent and making part of the same.

To all whom it may concern:

Be it known that we, EUSTIS P. MORGAN, of Saco, in the county of York, and State of Maine, and JAMES H. McMULLAN, of Biddeford, in the county and State aforesaid, have invented a new and useful Improvement in Roving-Frames, for the purpose of preparing cotton for spinning, and we do hereby declare that the following is a full and exact description of the construction and operation of the same, reference being had to the accompanying drawings, making a part of this specification.

Similar letters indicate the same parts in all of the figures.

Figure I is an end elevation; and

Figure II is a front view of the mechanism.

Our improvement in roving-frames relates mainly to the system of mechanism, herein described, for raising and lowering the bobbins in speeders, extensors, fly-frames, or slubbing-frames, the motion of the bobbins being vertical, and corresponding, in the distance and duration of the traverse, with the movements of the bolster-rail.

The preparation of the cotton-roving, from which the yarn or thread is to be spun, requires great care, and it is very important that the motion of the bobbin upon which the roving is wound be very steady, uniform and free from sudden tremor or vibration when the direction of the motion is changed at each end of the traverse.

The movement of the bolster or traverse-rail has usually been effected by a rack and pinion, and also by means of cams, pulleys, and chains.

In our invention the whole of the required motion is communicated by a series of curved levers, placed at intervals throughout the length of the frame, and having their centres at or near the rear of the frame.

By this arrangement of the parts, as herein described, the height of the frame is reduced, the motion is steady and uniform, there are few parts requiring lubrication and adjustment, and the mechanism is simple as compared with the machines heretofore used.

One of the ends of a roving-frame is represented at A.

Attached to the horizontal bar G, which extends the whole length of the frame, are the uprights or "samsons" B, which are placed at intervals, and afford support to the fixed rails C and D, and to other parts of the mechanism.

The curved frame-work F, at the back, and its continuation E, near the bottom of the machine, are firmly secured to the part G, and to the fixed rails C and D.

The shaft L, near the bottom of the frame, is driven in the usual manner, by any kind of mechanism that will cause it to rotate backward and forward alternately within fixed limits, this motion being the same, that is well known and used in all machines of this class.

Affixed to the shaft L is the spur-gear K, the teeth of which play into the teeth of the quadrant J, which forms a part of the curved arm or lever H.

This lever has its fulcrum or centre of motion at the stud I, affixed to the frame F.

The position of the stud in the slot 3 can be slightly varied, as may be required.

Motion is imparted to the traverse-rail Q, by that part of the forward end of the arm H that is embraced between the points marked O and P, the curvature or outline of the upper surface of the arm or lever, at this point, being such as to impart a uniform vertical motion to the traversing bolster-rail and the bobbin W.

The friction-roller 5 has its bearings in the stand 4, which is bolted to the back of the bolster-rail, while its periphery rests upon the curved part, O P, of the lever.

The lower part of the stand 4 is provided with two projections, which occupy a position just below a projecting flange or rib formed on the sides of the upper part of the arm H. This is intended to insure the descent of the rail Q, in case that any accidental obstruction should prevent the rail from falling back to its place.

Upon one side of the "samsons" B there is a vertical guide-rod or bar N, upon which the ends S S', of the guide-brace T, traverse. One of the arms of this brace T is bolted to the bolster-rail Q, and the two rear arms S S', slide upon the guide-bar N, as before mentioned.

At each end of the frame there is a vertical guide-bar M, which receives the branched ends of the bolster-rail Q, as at 6 and 7.

The two guide-bars, M and N, are exactly parallel with each other, and serve to give a firm and steady support to the rail and bobbins, as they move upward and downward.

The flier V occupies a fixed position as to its height, as represented in Fig. I, the roving 8 entering one of its arms at the top, and issuing at the bottom, 9, where it is wound upon the rising and falling bobbin W.

Upon the same shaft, L, that carries the spur-gear K, there is a fixed spiral pulley, X, from which a band or chain, 2, passes upward, and then over the fixed pulley Y. It is then attached to the counter-weight Z. This weight, Z, falls as the rail rises, holding it very nearly in equilibrium. In some cases it may be advisable to give the grooves of the pulley X, in which the chain runs, an unequal and gradually-increasing depth, in order that the weight Z may impart a variable amount of force, to correspond with the varying strain on the teeth of the quadrant J and the spur-gear K, as the lever H assumes different positions.

It is necessary that the bobbin W be raised and lowered at a perfectly uniform velocity, and to effect this a peculiar curvature is given to the upper surface

of the arm H, between the points O and P. As the free end of the arm H moves in the arc of a circle, having its centre at I, it is obvious that the vertical distance the point P passes through when the arm starts from its lowest point, is much less than the vertical distance traversed in the same time, when the arm is horizontal and the bobbin is raised to its highest point.

The length of the lever or arm, from the centre I to the bearing-point of the friction-roller 5, is also less when the arm is elevated.

The curvature at O P will vary with the length of the arm, the height of the centre I above the motor-gear K, and the distance that the bobbin is required to rise and fall.

The shape of the curved part of the arm upon which the friction-roller 5 rests, as shown in Fig. I, is the true curve required for moving the bobbins of a machine of the size and proportions represented in the drawings.

The number of spindles or bobbins in a machine may be varied at pleasure, a sufficient number of arms or levers being placed at intervals, parallel with each other, to effect the elevation of the bolster-rail.

Other forms and arrangement of the counterpoise and grooved spiral pulley, or its equivalent, may be used for balancing the weight of the transversing or bolster-rail, the action and effect of such devices being always adapted to and working in combination with the main features of our invention, as herein described.

What we claim, and desire to secure by Letters Patent, is—

1. The system or series of curved levers, driven by a segment-gear and pinion, or their equivalents, and having the free or outer end of each lever of such a curve as will impart to the bolster-rail, and the bobbins supported by it, a uniform motion in all positions of the lever.

2. In combination with the system of levers or arms, herein set forth, the spiral pulley X, and the counterpoise Z, or their equivalents, substantially as herein described, and for the purpose specified.

EUSTIS P. MORGAN. [L. S.]
JAMES H. McMULLAN. [L. S.]
